(57) **CLAIM**

The ornamental design for a hitch mountable table, as shown and described.

DESCRIPTION

FIG. 1 is a perspective view of the hitch mountable table showing our new design with the table in a raised position; FIG. 2 is a top plan view thereof;

FIG. 3 is a rear elevational view thereof;

FIG. 4 is a bottom plan view thereof;

FIG. 5 is a front elevational view thereof;

FIG. 6 is a left side elevational view thereof, the right side being a mirror image of the left shown;

FIG. 7 is a perspective view of the hitch mountable table with the table in a lowered position;

FIG. 8 is a top plan view thereof;

FIG. 9 is a rear elevational view thereof;

FIG. 10 is a bottom plan view thereof;

FIG. 11 is a front elevational view thereof; and,

FIG. 12 is a left side elevational view thereof, the right side being a mirror image of the left shown.
